UNITED STATES PATENT OFFICE.

JAMES CHESTER, OF NEW YORK, N. Y.

ILLUMINATED SIGN.

No. 873,921.

Specification of Letters Patent.

Patented Dec. 17, 1907.

Application filed November 20, 1906. Serial No. 344,242.

To all whom it may concern:

Be it known that I, JAMES CHESTER, a citizen of the United States, and a resident of the borough of Manhattan, county of New York, State of New York, have invented 5 new and useful Improvements in Illuminated Signs, of which the following is a specification.

My invention relates to signs and it has 10 for its object to provide an illuminated sign which will clearly bring out the letters of the sign and yet which will not dazzle the eyes which prevents the letters from being discernible only at short distances.

15 It is desired to produce a sign which can be read at long distances.

It also has for its object to produce a sign whereby the light will be evenly distributed in connection with each letter or wherein a 20 few and yet powerful lamps, electric or otherwise, may be used to produce the light for illuminating the sign and yet which will be evenly distributed. By this means a greater efficiency will be produced and a greater 25 economy will be accomplished in giving clearness to the letters.

By my invention I am enabled to use but a few lamps and yet produce a very efficient sign.

30 The invention consists in providing a reflector letter placed in front of a reflector surface.

The invention consists of a sign wherein the background is illuminated.

35 The invention consists in an illuminated sign wherein the background is illuminated while the letters though non-illuminated reflect the light to the background.

The invention consists in producing a sign 40 wherein the back of the letters are glazed or enameled and the background of the sign is glazed or enameled and the front of the letters is black whereby the letters will be clearly distinguishable in the daytime and 45 whereby the light will be evenly distributed in the nighttime.

The invention also consists in other features set forth in the following description of my invention, shown in the drawings and 50 claimed in the claims.

Referring to the drawings, Figure 1 is an illustration of the front view of the sign. Fig. 2 is a vertical sectional view taken along the line 2, 2 indicated in Fig. 1. Fig. 3 is a 55 horizontal sectional view of a portion of the letter B taken along the line 3, 3 indicated

in Fig. 1. Fig. 4 is a closed letter to be used in connection with gas lights and is a sectional view of such a letter. Fig. 5 is a modification of my invention and consists of 60 a sectional view of the letter I. Fig. 6 is a horizontal sectional view of the letter shown in Fig. 5. Fig. 7 is another modification of my invention wherein the background is of substantially the same shape as the letter. 65 Fig. 8 is a horizontal sectional view taken along the line 8, 8 indicated in Fig. 7.

I shall now describe my invention more in detail. I have shown the preferred form of my invention in the drawing but it is to be 70 understood that the details that I am about to describe may be varied within the scope of the appended claims by those skilled in the art without in any way modifying the spirit of the invention.

75 1 in Figs. 1, 2, 4 and 5 indicates the background of the sign. The front surface 2 of the background is made so that it will reflect light. It may be painted white but it is preferably made of white enamel or covered 80 with other glazing material. In the form of invention I have shown, the surface is covered with white enamel. The shape of the background is such that its cross section is parabolic, so that the greatest reflective 85 power can be obtained from the reflector background 2 and so that the rays of light will be seen from the greatest distance. The background may be supported in any of the well known ways in which signs are supported. 90

95 The letters are supported in front of the reflector surface 2. They may be supported in any convenient way so that the letter is somewhat remote from the background and so that the lamps which illuminate the sign may be placed in the foci of the reflector surface. The means that I have shown for supporting the letters consists of a pair of rods 3, 4 located near the top and the bottom of the 100 background of the sign. The rods are supported at their ends by brackets 5, 6, 7 and 8. The brackets are attached to the reflector background 1 by means of rivets or screws. Clips 9 and 10 are attached to the 105 rear surface of the letters. The clips consist of two spring tongues 11 and 12 which are movable with reference to each other, and are adapted to grasp and securely hold the rods. The letters may then be readily 110 placed in front of the background of the sign by merely pressing the letter and its clip

against the rods. The tongues of the clips will separate and the clips will thus readily seize and hold the rods thereby securing the letter to the sign. The letter can be easily removed by simply separating the tongues and pulling the letter off. This is particularly valuable in connection with signs used for bulletins or wherein it is desired to modify the sign daily.

- 10 The curvature of the letters and the rearward extension of the letters so that the letters extend more or less around the source of illumination causes the rays of light which pass in proximity to the edge of said letters and which rays are thereby diffracted to radiate laterally. Hence the diffractive diffusion of the light in front of said letters is obviated and the letters more sharply delineated.
- 20 The preferred form of the letter that I have used has an inner surface which is of such a form that it will act as a reflector. The surface 13 of the interior of the letter is preferably made of white enamel. It may 25 be painted white or it may be made of any glazed material or it may be made of any material which will produce the most effective results as a reflector. On the inner surface 13 of the letter there are mounted one or 30 more lamps.

The lamps may be of any character desired. In Figs. 2, 3, 5 and 6 I have illustrated electric lamps and in Fig. 4 I have illustrated a gas mantle lamp. In the form 35 illustrated in Figs. 2 and 5 the lamp 14 is supported on the bracket 15 which is attached to the letter. Electric wires 16 and 17 lead from the lamp 14. If it is desired the wires 16 and 17 may lead to a cable. In the 40 form of invention that I have shown the connecting wires 16 and 17 are connected to the clips 9 and 10 which are located at the top and the bottom of the letter. The rods 3 and 4 are connected to the main line through 45 the supports 5 and 6 which may be insulated from the reflector surface 1. The electric current then passes through the supports 5 and 7 and to the rods 3 and 4 thence to the clips 9 and 10 and to the lamp 14. The 50 lamp 14 is located with respect to the reflector 2 so as to obtain the best results.

In the form of the invention shown in Fig. 4 the body of the letter is inclosed by means of a glass plate 18 which is located on the 55 back of the letter. A pipe 19 passes through the reflector 1 and into the inclosed space of the letter. The pipe is connected with a mantle burner 20. The glass prevents the gas light from being blown out and moreover 60 the white enamel reflector reflects the white light coming from the mantle with great effectiveness.

In Fig. 5 I have shown another modification wherein the letter is provided with sides 65 located at right angles to the body of the let-

ter. I have shown a sectional view of the letter I having the body 21 and the sides 22, 23 which are located at right angles thereto. The sides 22 and 23 prevent diffraction of the light about the edge of the front of the letter 70 and operate to throw the light upon the reflector behind the letter. This prevents diffracted light from passing to the front of the letter which would otherwise produce diffusion of light in front of the letter. The interior of the surface 24 of the letter is enameled as in the other cases and the exterior surface 25 is also blackened.

In Figs. 7 and 8 is shown another modification of my invention wherein the reflector 80 or background 26 is of the same shape as the letter 27. This form of the invention is especially advantageous when very large or enormous signs are to be used. The background 26 may be supported in any of the 85 ways wellknown in the art. The letter 27 is attached to the background of the letter by means of rods 28 and 29 or in any other suitable way. The letter 27 is made in the form of a reflector and its inner surface may be enameled or glazed so as to increase its power as a reflector while the exterior or front of the letter may be painted black. The background of the letter is also made in the form of a reflector and operates to reflect the light 90 forward, that is, in front of the letter. Electric lamps 30 and 31 are provided which are located between the two reflectors and in close proximity to the letter 27. The background 26 operates to throw the light forward 100 and diffuse it. This arrangement causes the letter 27 to appear dark with a rim of bright light surrounding the black letter 26.

The description given above is merely that of a particular construction shown which embodies my invention but this particular construction can be varied within the scope of the appended claims without in any way avoiding the essence of what I consider to be my invention.

What I claim is new and desire to secure by Letters Patent is as follows:

1. In an illuminated sign the combination of a background, a light producing means, one or more letters or symbols and means for causing the light to illuminate the said background and for preventing the light from illuminating the said letters and to produce the effect of an illuminated surface having thereon black letters.
2. In an illuminated sign the combination of a background, a light producing means, one or more letters or symbols located in front of the said light producing means, the said letters or symbols having means for preventing diffracted light from passing to the front of the said letters.
3. In an illuminated sign the combination of a background, one or more letters or symbols, a light producing means located in the

115

120

125

130

rear of said letters and means whereby the rays of light may be reflected from the said letters to the said background and from the said background to the beholder of the sign.

5 4. In an illuminated sign the combination of a reflector background, one or more letters or symbols, a light producing means located behind the said letters or symbols, the said letters or symbols having on their rear faces 10 reflector surfaces adapted to reflect the light to the said reflector background and contoured to prevent the diffractional diffusion of the light in front of the letters.

5. In an illuminated sign the combination 15 of a reflector background, a light producing means, one or more letters or symbols, the said letters or symbols having reflector surfaces, the said light producing means being located in the vicinity of and in the rear of 20 said letters or symbols, the said letters having means to prevent the light from being diffractionally diffused in front of the letters.

6. In an illuminated sign the combination 25 of a background, a light producing means, one or more letters or symbols, the said light producing means being supported on the said letters, means for supporting the said letters or symbols on the background and for connecting the said light producing means 30 with an external circuit.

7. In an illuminated sign the combination 35 of one or more letters or symbols, a reflector background located at some distance in the rear of the said letters or symbols and in full view of the beholder of the sign, a light pro-

ducing means located in proximity to the surface of the said letters or symbols and between the said symbols or letters and the said background.

8. In an illuminated sign the combination 40 of one or more letters or symbols, a reflector background, a light producing means, the said letters or symbols having means to direct the said light to the rear of the said letters or symbols and the said reflector background being adapted to direct the light forward so that the rays of the said light will pass by and on the outside of the said letters.

9. In an illuminated sign the combination 45 of one or more letters or symbols having concave surfaces located on the rear thereof, a reflector background having a concave surface located on the front thereof and in full view of the beholder of the sign, a light producing means located in the concavity of 50 each of said letters or symbols.

10. In an illuminated sign the combination 55 of one or more letters or symbols having concave surfaces located on the rear thereof, a background, and a light producing means located in the concavity of each of said letters or symbols.

In testimony whereof, I have signed my name to this specification, in the presence of two subscribing witnesses.

JAMES CHESTER.
